UNITED STATES PATENT OFFICE

2,039,484

VENTILATOR

Thomas A. Heppenstall, Cheshire, England, assignor to H. H. Robertson Company, Pittsburgh, Pa., a corporation of Pennsylvania

Application December 8, 1932, Serial No. 646,272
In Great Britain January 12, 1932

3 Claims. (Cl. 98—84)

This invention relates to ventilators of that type in which are employed an eduction pipe, a cap member, and a storm band, such for instance as is shown in United States Letters Patent No. 5 1,589,581 dated June 22, 1926.

The present invention has for its object to provide ventilators of the type referred to with an angular storm band without diminishing the efficiency of the ventilator.

10 The angular storm band is preferably made square in form and the eduction pipe and cap member are preferably made circular, and when these parts are assembled, the ventilator is provided with a gas outlet having portions of different widths, being wider at the corners than at the sides of the ventilator. The wider portions of the gas outlet located at the corners of the angular storm band, afford opportunity for rain driven downward into the ventilator at different 15 angles, to enter the eduction pipe and descend into the structure upon which the ventilator is mounted.

In accordance with the present invention, the 20 ventilator is provided at the wider portions of the gas outlet with means for preventing the rain which may enter the top of the ventilator at the corners thereof, from passing into the eduction pipe, without materially interfering with the flow 25 of gases from the eduction pipe out of the ventilator through the gas outlet passage thereof, and therefore without diminishing the efficiency of the ventilator.

These and other features of this invention will 30 be pointed out in the claims at the end of this specification.

Fig. 1 is a plan view of one form of ventilator embodying this invention;

Fig. 2, a vertical section on the line 2—2, Fig. 40 1, and

Fig. 3, an enlarged detail of one corner of the 45 ventilator shown in Fig. 1.

Referring to the drawings and particularly Fig. 2, 10 represents the eduction pipe; 12, the cap member; and 13, the storm band of a ventilator embodying the invention.

The eduction pipe 10 is preferably circular in form and is provided with a lip 14, and the cap member 12 is shown as a circular disk of substantially the same diameter as the eduction pipe 10 and provided with a lip 15 of substantially the same diameter as the lip 14 on the eduction pipe.

The cap member 12 and the upper end of the eduction pipe 10 are located in an angular storm band 13, preferably square as shown in Fig. 1, and

the space between the cap member 12 and the storm band 13 constitutes the gas outlet for the ventilator.

The gas outlet between the cap member 12 and the center portion of the sides of the storm band 5 is materially narrower than the portion of said gas outlet between the corners of the storm band and the cap member, as clearly shown in Fig. 1, the said gas outlet increasing in width from the center of the sides of the storm band toward the 10 corners thereof.

Owing to the greater width of the gas outlet passage at the corners of the storm band, greater opportunity is afforded for rain driven down into the ventilator at different angles, to pass into the 15 eduction pipe and thence into the structure upon which the ventilator is mounted, which is highly objectionable.

To prevent rain which may enter the ventilator at the corners thereof from passing into the 20 eduction pipe, baffling means are located between the cap member 12 and the storm band 13 at the corners of the latter, and it is preferred to make the baffling means in the form of continuous circular bands or members 16, 17, which are of different diameters and are provided with peripheries of 25 different widths.

The band or member 16 of larger diameter is 30 preferably made of a diameter substantially equal to the width of the storm band, so that the said band or member is substantially tangent to the inner surfaces of the sides of the storm band as represented in Fig. 1.

The band or member 17 is of smaller diameter 35 than the band or member 16 and is located between the lip 15 on the cap member 12 and the storm band 13, and the band or member 17 extends above and below the lower edge of said lip.

The bands or members 16, 17 are supported by 40 vertically arranged corner plates or vanes 18, which are suitably fastened to the storm band at the corners thereof and extend diagonally toward the axial center of the eduction pipe 10 and cap member 12.

The vanes or plates 18 may and preferably will 45 be constructed so as to form supporting members for the eduction pipe 10, cap member 12, and a baffle ring or band 19, which it is preferred to employ and which is located between the cap member 12 and the eduction pipe 10.

The vertically arranged corner vanes or plates 18 are provided on their inner edges with inclined slots 20, 21 for the reception of the lip 14 on the eduction pipe 10 and the baffle ring or 55

band 19, as represented in Fig. 3, and the top edge portion of the vanes or plates 18 are provided with inclined projections or extensions 22 upon which rests the lip 15 on the cap member.

5 By reference to Fig. 3, it will be seen that the band or member 17 co-operates with the cap member 12 and the baffle ring 19 to effectively prevent rain driven into the top of the ventilator at the corners thereof and at an angle approximating the horizontal, from passing over the top end of the baffle ring 19 and descending into the eduction pipe 10 and thence into the structure on which the ventilator is mounted.

It will also be seen that the band or member 16 co-operates with the baffle ring 19 and the lip 14 on the eduction pipe 10 to prevent rain driven into the ventilator at a different angle from entering the eduction pipe below the baffle ring 19.

It will further be observed that the wider portions of the gas outlet passage of a ventilator having an angular storm band is effectively protected against rain, driven into the wider portion of the gas outlet passage, from entering the eduction pipe and the structure on which the ventilator is mounted, which would not only be objectionable to users of the structure but also would materially diminish the efficiency of the ventilator.

A ventilator having an angular and preferably square storm band is capable of general use on stationary structures, such as buildings and the like, but is particularly adapted for use on movable structures, such as motor buses, railway cars, and other movable vehicles, and when used on movable structures, it is preferred to employ a cap member of the character herein shown, which does not project above the square storm band and allows the ventilator to be made compact without decreasing its efficiency, and to present 40 a pleasing and inconspicuous appearance, especially on motor buses, railway cars, and like vehicles.

Having thus described the invention, what is claimed is:

45 1. In a ventilator, in combination, an eduction pipe, a cap member located above and in line with said eduction pipe, a baffling ring between said eduction pipe and cap member, a storm

band of greater area than said eduction pipe and cap member and of a height greater than the distance between the eduction pipe and cap member angular in cross section with the walls of its angles continuous and vertically arranged and forming vertically arranged corners in said storm band, said angular storm band forming with said cap member a gas outlet passage about the cap member having portions of greater width between the vertically arranged corners of the storm band 10 and said cap member than between sides of said storm band and said cap member, and circular bands of different diameters in the portions of the gas outlet of greater width and arranged with relation to said baffling ring to prevent rain from 15 passing above and below said baffling ring into said eduction pipe.

2. In a ventilator, in combination, a circular eduction pipe, a circular cap member above and in line with said eduction pipe, a rectangular 20 storm band surrounding the eduction pipe and cap member and of a height greater than the distance between the eduction pipe and cap member, said rectangular storm band forming with the cap member a gas outlet surrounding the cap 25 member and of greater width at the corners of said rectangular storm band, and a circular band interposed between the cap member and the storm band at the corners thereof.

3. In a ventilator, in combination, an eduction 30 pipe, a circular cap member above and in line with said eduction pipe and separated therefrom by a substantial space, an angular storm band surrounding the eduction pipe and cap member and having the walls of its angles vertically arranged and extended above the circular lower edge of the cap member and below the upper edge of the eduction pipe and forming with the circular lower edge of the cap member a gas outlet passage having the portion thereof between the vertical walls of its angles of greater width than that of the portions between the cap member and the non-angular vertical portions of the storm band, and baffling means in said wider portion of said 40 gas outlet passage to prevent rain passing over 45 the upper edge of the angular portion of the storm band from passing into the eduction pipe.

THOMAS A. HEPFENSTALL.
